METHOD OF FABRICATING AN AUTOMOBILE HEATER

Arthur W. McNeish, Detroit, Mich.

Application July 23, 1937, Serial No. 155,158

5 Claims. (Cl. 113—118)

This invention relates to an automobile heater and more particularly to a method for fabricating the same.

In the fabrication of a heater of the exhaust type, such as shown in my copending application Serial No. 96,726, filed August 19, 1936, particularly where the heater is used with an internal combustion engine having two banks of cylinders each with a separate exhaust pipe, the heater must be provided with two separate pipes for connecting with these two separate exhaust pipes. These two pipes are positioned in suitable openings provided in the end plate of the heater and copper welded or brazed therein. However, each of these two pipes must be properly positioned and fixed in the end plate of the heater so that they will accurately join with the ends of the separate exhaust pipes leading from the individual banks of cylinders of the engine. Considerable difficulty has been encountered in holding the pipes in the proper position in the openings in the end plate while the heater was being passed through and copper welded or brazed in the hydrogen furnace.

It was proposed to first properly position the pipes in the openings in the end plate of the heater and then by means of an acetylene torch weld the exhaust pipes in the openings in two or more spaced spots before passing the heater through the hydrogen furnace for copper welding. However, this method proved impractical because for some unexplainable reason the copper weld or brazing was invariably defective at the points at which the pipe and end plate were torch welded thus permitting the escape of exhaust gases at this point which is highly undesirable. It is also impractical to hold the pipes and heater in a jig while passing them through the hydrogen furnace.

It is the object of this invention to overcome this difficulty and fabricate a heater in which the parts are copper welded or brazed together and in which the exhaust pipes will be fixed in the proper position and in which the copper or brazed joint between the end plate and the pipe will be air-tight.

In the drawing:

Fig. 1 is a side elevation partly in section showing my heater with the two exhaust pipes.

Fig. 2 is an end elevation of the heater.

Fig. 3 is a section along the line 3—3 of Fig. 2.

Referring more particularly to the drawing there is shown a heater generally of the type shown in my above-mentioned application consisting of an outer casing 1, an inner casing 2, end plates 3 for closing the end of the outer casing

1 between the end of the inner casing 2 and outer casing 1. The heater also includes an end plate 4 for the end of the inner casing 2.

The inner casing 2 is spaced from the outer casing 1 to provide a chamber 5 through which the air circulates about the casing 2. The air passes into the casing 1 through inlet 6 and out through outlet 7. The exhaust gases pass through the inner casing 2 and are conducted to the casing 2 by means of the curved exhaust pipes 8 and 9. 10 One pipe 8 connects up with the exhaust pipe 10 leading from one bank of cylinders of an internal combustion engine, such as a V type motor, and the other pipe 9 connects up with the other banks of cylinders of said motor.

The exhaust gases pass through casing 2 and into the outlet pipe 11. Obviously the heater must occupy a given definite space adjacent the motor and beneath the hood of the automobile. Not only must the heater be properly positioned 20 in the space provided beneath the hood, but the pipes 8 and 9 must be individually positioned with respect to the motor exhaust pipes 10 so that they will properly align with these pipes. Thus, the pipes 8 and 9 must be held in a very definite 25 position one with respect to the other, and after being positioned in the openings 12 provided therefor in the end plate 4, must be held in fixed relation with these openings so that the pipes 8 and 9 will not turn in the openings 12 and will not 30 tilt in the openings 12. At the same time, since it is proposed to braze the joint between the pipes 8 and 9 and the openings 12 in the end plate 4, nothing must be done which will cause this joint to be defectively brazed so that exhaust gases will 35 leak through the joints between the pipes, 8, 9 and the openings 12.

To this end, after the pipes 8 and 9 have been properly positioned in the openings 12 so that they will line up with the motor exhaust pipes 40 10 leading from the banks of the motor, and so that the pipes 8 and 9 will be positioned properly with respect to the end plate 4 and heater case, a bridge 13 in the form of a U with outturned ends 14 is positioned between the pipes 8 and 9 with 45 the outturned ends 14 positioned against the outer face of the end plate 4. The end plate 4 is provided with a press fit in the end of the inner casing 2 so that it will not move with respect to the casing 2 even when supporting the weights of 50 the pipes 8 and 9 while passing through the hydrogen furnace.

The bridge 13 is preferably although not necessarily made of a strip of metal having about the same width as the distance between the pipes 8 55

and 9 in that area where the bridge is positioned. The outturned ends 14 of the bridge are welded as at 16 to the end plate 4 and then after the pipes 8 and 9 have been properly located with respect 5 to each other, the heater casing, and the exhaust pipes from the engine, the bridge is then torch welded as at 17 to the pipe 8 and as at 18 to the pipe 9. The welds as at 17 and 18 are preferably made with a welding torch and welding wire. Thus, the welds 17 and 18 can, if desired, extend a quarter or even a half an inch along the edges of the bridge 13 and connect the bridge 13 to the pipes 8 and 9 for a distance of a quarter or even half an inch. The length and 15 extent of the weld, of course, can be varied depending upon the conditions obtaining such as the weight of the pipes 12, the length and the handling to which the heater is subjected before and during its passage through the hydrogen furnace.

The openings 12 are provided with turned flanges 19. Upon passing through the welding furnace an excellent and air-tight weld will now be obtained between the pipes 8 and 9 and the 25 flanged openings 12 in the end plate 4. It will be noted that the welds connecting the bridge 13 to the end plate 4 and to the pipes 8 and 9 are spaced from the joints between the pipes 8 and 9 and the openings 12 in the end plate 4 and thus 30 do not at all interfere with the copper brazing or welding of the heater.

I claim:

1. A method for fabricating a sheet metal automobile heater of the type comprising a sheet metal casing through which the exhaust gases of the motor are passed in heat exchange relation but out of communication with the air to be heated, a sheet metal closure plate for the end of said casing having an opening therein and a 35 pipe adapted to fit in the opening in the end plate and connect with the exhaust passageway of the motor to conduct the exhaust gases from the motor into the said casing, said method comprising the steps of inserting the exhaust pipe in the opening in the end plate, positioning the said pipe in a predetermined position with respect to the said end plate and so that it will connect with the motor exhaust passageway, and while the 40 pipe is thus positioned welding a metal bridge member to the said pipe and closure plate at points spaced from the joint between the pipe and the opening in the end plate, and thereafter brazing the said pipe in the opening in the end plate to secure an air-tight joint between the end 45 plate and the pipe and to fix the pipe in the said opening.

2. A method for fabricating a sheet metal automobile heater of the type comprising a sheet metal casing through which the exhaust gases are passed in heat exchange relation but out of communication with the air to be heated, a sheet metal closure for the end of said casing having an opening therein and a pipe adapted to fit in the opening in the end plate and connect with the exhaust passageway of the motor to conduct the exhaust gases from the motor into the said casing, said method comprising the steps of inserting the exhaust pipe in the opening in the said end closure, positioning the said pipe in a predetermined position with respect to the said end closure and so that it will connect with the exhaust motor passageway, and while the pipe is thus positioned torch welding a metal bridge member to the said pipe and end closure both at

points spaced from the joint between the pipe and the opening in the end closure and thereafter copper brazing the said pipe in the opening in the end closure to secure an air-tight joint between the end closure and the pipe and to fix the 5 pipe in the said opening.

3. A method for fabricating a sheet metal automobile heater of the type comprising a sheet metal casing through which the exhaust gases are passed in heat exchange relation but out of communication with the air to be heated, a sheet metal end closure having two openings therein and a pair of pipes adapted to fit in the openings in the end plate and connect with the exhaust passageway of the motor to conduct the exhaust 10 gases from the motor into the said casing, said method comprising the steps of inserting the exhaust pipes in the openings in the end closure, positioning a metal bridge member between the said exhaust pipes and against the said end closure, positioning the said pipes in predetermined position with respect to the said end closure and each other and so that they will connect with the motor exhaust passageways, and while the pipes are thus positioned welding the 15 metal bridge member to the said pipes and end closure at points all of which are spaced from the joints between the pipes and the openings in the end closure and thereafter brazing the said pipes in the openings in the end closure to secure 20 an air-tight joint between the end closure and the pipes and to fix the pipes in the said opening.

4. A method of fabricating a sheet metal automobile heater of the exhaust type comprising forming a plurality of openings in a wall of the 35 said heater, inserting a pipe in each of said openings, positioning a sheet metal bridge member adjacent the said pipes and in contact with the said wall of the said heater, positioning the said pipes in a predetermined position with respect to the said wall and with respect to each other, and while the pipes are thus positioned welding the 40 said metal bridge member to each of said pipes at points spaced from the said wall of the said heater and also welding the metal bridge member 45 to the wall of the said heater at a point spaced from the joint between the said pipes and the openings in the said wall and thereafter brazing the said pipes in the openings in the said wall to secure an air-tight joint between the said wall 50 and the pipes.

5. A method of fabricating a sheet metal automobile heater of the exhaust type comprising forming a plurality of openings in a wall of the said heater, inserting a pipe in each of said openings, positioning an approximately U shaped sheet metal bridge member between the said pipes with the ends of the bridge member in contact with the said wall of the heater, positioning the said pipes in a predetermined position with respect 60 to the said wall of the heater and to each other, and while the pipes are thus positioned welding the metal bridge member to the said pipes at points spaced from the joint between the pipes and the openings in the wall of the heater and also welding the ends of the U bridge member 65 to the wall of the heater at points spaced from the joints between the openings in the wall and the said pipes, and thereafter copper brazing the said pipes in the openings in the wall of the 70 heater to secure an air-tight joint between the wall and the pipes and to fix the pipes in the said openings in said predetermined position.

ARTHUR W. MCNEISH.
